UNITED STATES PATENT OFFICE

ELIZABETH CONSTANTINE AUER AND HANNAH M. HART, OF CHICAGO, ILLINOIS

MULTIPLEX HEATER FOR PERMANENT-WAVE MACHINES

Application filed March 23, 1928. Serial No. 264,059.

This invention relates, broadly stated, to heating elements, and is more particularly concerned with a novel multiplex heating element for applying, to hair, permanent waves of various character. It is designed to replace the well known tubular heater used at present in connection with permanent wave machines, and its principal object is to furnish a means for applying waves of different design, such as ordinary round curl waves and so-called Marcel waves in a simple and highly efficient manner.

The permanent wave machine, as is well known, comprises a plurality of tubular heating elements, attached by cords to a common stand. The operator winds a strand of hair on a tapering round curler rod, fastens the hair to this rod, and then wraps a moist pad around it. Thus prepared, the rods are inserted into the heaters on the machine. When current is applied, the various strands of hair are steamed and baked in place, producing simple round coils or curls. These are then manipulated by combing, brushing and a special setting process, and the finished product is called a permanent wave.

The wave produced in this manner is not a true imitation of a natural wave due to the circular character of the curls. Discriminating clients prefer, therefore, the so-called Marcel wave which is applied manually by an operator manipulating a curling iron of special construction.

In the patent to Hannah M. Hart, No. 1,768,055 of June 24, 1930, is disclosed a waving device designed to overcome the deficiency of the usual permanent wave machine, by furnishing a simple curler fork which serves for imparting to the hair a wave in nearly perfect imitation of a natural wave. This curler fork is used in place of the usual round curler rod. A strand of hair is arranged on the prongs of the curler fork, each prong serving as an axis for a series of curls. Thus arranged, the strand of hair on the fork is subjected to the usual process of steaming and baking in a suitable heater. The wave produced in this manner differs substantially from the wave produced by employing a simple round curler rod. It produces two ad-

joining series of curls, which, when brushed and combed, exhibit a natural appearance similar to a manually marcelled wave.

It is the principal object of this invention to provide a heater which may be used for producing either a "round curl" wave or a Marcel wave, regardless of the device which is employed for initially arranging the hair. This initial device may be either a round tapering rod as usually employed, or it may be a device, such for example as shown in the above mentioned patent.

The heater contemplated in the present case consists of a primary heater having a tubular heating member for receiving a strand of hair arranged on the prongs of a curler fork; a heating element is arranged around the heating member and insulating means cover the heating element to prevent heat radiation to the outside. A contact assembly is concealed in said primary heater, having springs to maintain normally a connection between the heating element and current supply conductors permanently connected to the primary heater. A separate secondary heater is provided, which is adapted to be inserted into the tubular heating member of the primary heater. This latter heater has a tubular heating member for receiving a strand of hair arranged on a round curler rod; located around said heating member is a heating element having insulating means to prevent heat radiation to the outside exactly as in case of the primary heater. There are also contact means provided in the secondary heater which are adapted to cooperate with the contact assembly in the primary heater when the secondary heater is inserted therein.

When it is desired to apply a Marcel wave, the primary heater will be used. If an ordinary round curl wave is to be applied, the operator simply inserts the secondary heater into the primary heater. This action causes the cooperating contact assembly in the primary heater to disconnect the current supply conductors from the heating element therein and to substitute the heating element in the secondary heater.

Another embodiment of the invention is concerned with a heater having movable heat-

ing elements. These elements are normally in a position to form a large oval tubular opening for receiving a strand of hair arranged on a curler fork to produce a Marcel wave. By operating knobs provided on the outside of the heater, the elements are displaced to form a small circular opening for receiving a strand of hair arranged on the usual curler rod to produce a round curl wave.

It will be seen from the above discussion that the heating element disclosed in the present case permits the application of either a round curl wave or a Marcel wave, each of which necessitates a different curler device (rod or fork) without any trouble or change whatever. It will also be appreciated that the insulating means surrounding the heating elements of the primary and of the secondary heater furnish a very efficient device, since the heat will always be at the proper place, i. e., close to the strand of hair wound on the curler device in use.

The invention is illustrated in the accompanying three sheets of drawings which form a part of this specification, and in which

Fig. 1 shows the primary heater in perspective;

Fig. 2 illustrates a longitudinal cross section taken on the line 2-2 of Fig. 1, with some parts broken away to keep the drawing simple and lucid;

Fig. 3 is a cross section on line 3-3 of Fig. 1;

Fig. 4 illustrates a detail part carrying the contact mechanism;

Fig. 5 illustrates the secondary heater in perspective;

Fig. 6 is a cross section taken on line 6-6 of Fig. 5;

Fig. 7 is a cross section on line 7-7 of Fig. 5;

Figs. 8 and 9 show a locking mechanism for securing the secondary heater in place when inserted in the primary heater;

Fig. 10 shows a modification of the primary heater in cross section with the contact mechanism arranged circularly on the inside of the heater;

Fig. 11 illustrates the cross section of a modification of the secondary heater which may be used in connection with the primary heater shown in Fig. 10;

Fig. 12 shows the longitudinal cross section of a modified heater having movable elements;

Fig. 13 illustrates a transverse cross section of the heater shown in Fig. 12;

Fig. 14 shows a partial longitudinal cross section of the heater shown in Fig. 12, but taken in another plane;

Fig. 15 shows a wiring diagram for the movable heating elements;

Fig. 16 shows a detail part used in the

above heater for guiding the movable elements; and

Fig. 17 illustrates the position of the elements when used for making a round curl wave. The opening being circular, as contrasted with the oval opening shown in Fig. 13.

The detailed description of the various parts shown in the drawings, and of the operation of the device, will now be presented.

Referring now to the drawings, Figs. 1, 2 and 3 illustrate the primary heater. It consists of the outer or cover shell member 1 which is provided at its lower end with a circular inset to serve as a shoulder for holding the insulating member 8 and the heating element 7. Attached to this cover shell 1 is a cuplike inner heating member 9. At the upper closed end of member 9 are two openings 10 and a threaded hole for receiving a screw 12 which is provided for holding the insulating plate 11 in place, resting on the member 9 and on the end portion of the shell 1.

The insulating plate 11 may be of any well known and desirable material. The plate is mounted on the heating member 9 as was described in the foregoing paragraph, and its purpose is to hold contact members best seen in Fig. 4. Two of these contact members are resilient springs designated 13 and 17 which are mounted on the plate 11 by means of screws 14 and 18.

Two cooperating contact springs are mounted stationary on the plate 11 by means of screws 16 and 20. The latter as well as the former contact springs are provided with contact points which are normally in engagement, as shown in case of the contact springs 13 and 15 in Fig. 2. The movable contact springs 13 and 17 are also provided with contacts 21 and 22 which project normally through holes in the insulating plate 11 and through the openings 10 in the heating member 9. The entire heater is closed by means of a cup member 2 which has an opening to receive the protecting wire coil 3, inside of which is the cable 4 carrying the current supply conductors 23 and 24. These conductors are permanently connected to the

springs 13 and 17, as is shown in Fig. 4. Since these springs are in contact with the stationary springs 15 and 19, and since these latter springs are permanently connected with the terminals of the heating element 7, as is best seen in Fig. 2, it will be obvious that the heating element 7 is normally always connected to the current supply conductors. It will be understood of course that a switch may be provided individual to the heater if desired. Usually, however, the switch for turning on the current, is located conveniently at the junction of two heaters.

The auxiliary or secondary heater will be described next with reference to Figs. 5, 6 and 7.

It comprises a shell member 27 having a knurled part 28 rigidly attached to it. Arranged inside of this shell and resting against the part 28 are the insulator 33 and the heating element 32, and mounted on the part 28 by means of a threaded end is the heating member 31. It will be seen that the arrangement of the various parts corresponds exactly to the arrangement shown in connection with 10 the primary heater. The part 28 is knurled in order to provide for taking the secondary heater conveniently out of the primary heater. The shell 27 is also provided with a shoulder for receiving the insulator plate 29 which is 15 fastened to the assembly by screw 40 engaging the bottom side of the heating member 31. Two contact members 34 and 35 are mounted on the plate 29 by means of nuts 36 and 37, and permanently connected to these 20 contacts are the terminals 38 and 39 of the heating element 32.

If it is desired to steam and bake a Marcel wave, the operator will insert the strand of hair arranged on the curler fork into the 25 opening 6 in the heater shown in Figs. 1 and 2. Due to the insulation of the heating element, the heat produced will be concentrated to the inside, keeping the outside of the heater cool during the entire process. However, if 30 it is desired to treat an ordinary round curl wave, this may be done by simply inserting the heater shown in Figs. 5, 6 and 7 into the opening 6 of the primary heater. The curler rod is then inserted into the opening 30 in 35 the secondary heater.

Referring now to Figs. 8 and 9, these figures illustrate schematically how the secondary heater may be locked in place in the primary heater. As shown in Fig. 8, a groove 42 may be provided near the lower end of 40 the member 9, and a spring member 43 may be inserted in the groove 42 in such a manner that its middle part projects into the opening 6 of the inner shell of the heater. The 45 secondary heater shown in Figs. 5, 6 and 7 may be provided with a groove or notch corresponding to the resilient spring in the opening 6 of the primary heater. Now, when the 50 primary heater, the spring 43 will engage the groove in the outer shell of the secondary heater, and the heater will thus be locked in place. It will be understood of course that the locking arrangement has been shown 55 by way of example only, and that any other arrangement may be adopted to equal advantage.

Figs. 10 and 11 show modifications of the primary and of the secondary heater, respectively, and will be explained next.

It may be desirable to preserve the openings 6 in the primary heater and 30 in the secondary heater, throughout the entire length of the device. In such a case, the 60 modifications shown in Figs. 10 and 11 may

be adopted, which show the arrangement of the contacts circularly inside the upper ends of the heaters. All parts are designated with reference numerals corresponding to the designations in previous figures, with the addition of a prime. 70

Stationary contact springs 15' and 19' are shown mounted on the inside of the heater Fig. 10, insulated against the heating member 9'. Cooperating resilient contact springs 13' and 17' are mounted circularly inside the cover shell 1' and, of course insulated therefrom. These contact springs are provided with contact points as usual, and are normally in engagement with each other. 75 Therefore, the heating element 7' which has its terminals 25' and 26' permanently connected to the contact springs 15' and 19' is maintained connected to the usual current supply conductors, which may be permanently connected to the springs 13' and 17'. 80 There are openings in the heating member 9' and through these openings project contacts 21' and 22'. A detailed view of how these curved springs are mounted on the corresponding members of the heater has not been shown, because the detailed arrangement of these parts is believed to be sufficiently illustrated in the figure. 85

Fig. 11 shows a secondary heater which may be employed in connection with the modified primary heater described above. The heating member 31' is screwed into the lower part of the shell 27' which encloses the heating element 32' and the insulator 33'. The terminals 38' and 39' of the heating element end in contact points as shown. At the upper end of the shell 27' and inside of it are two contact springs 44 and 45 provided with contact points to engage the contacts of the heating element, and with contacts 34' and 35' to engage the contacts 21' and 22' of the primary heater when the secondary heater is inserted therein. 95

The operation of these modified heaters just discussed will be obvious from the drawings and from the explanations furnished in connection with previously discussed figures. However, there is a slight difference in handling the heaters shown in Figs. 10 and 11, which will be briefly explained. It will be seen from Fig. 11 that the springs 44 and 45 rest against a ring 46, forcing this ring normally upward against the angle furnished by the shell member 27'. This ring 10 is of insulating material (the springs 44 and 45 being also mounted on the inside of the member 27' by means of an insulator) and has plungers projecting through suitable openings in the cover edge and terminating 110 in an operating ring 47. Now, when the heater Fig. 11 is inserted into the opening of the heater Fig. 10, the operator will depress the ring 47 and thereby push the insulator ring 46 against the springs 44 and 115 120 125 130

45. Accordingly, these springs are forced to make contact with the heating element 32' and the contact members 34' and 35' are forced outwards to engage the corresponding movable contacts 21' and 22' of the primary heater. These latter contacts move the springs 18' and 17' out of engagement with the springs 15' and 19', disconnecting the heating element of the primary heater as usual. Therefore, the contacts 34' and 35' serve also as locking members for securing the secondary heater in place in the primary heater. It will be understood of course, that the openings through which the contacts 21' and 22' project, as well as the openings in the secondary heater provided for contacts 34' and 35' may be equipped with insulating bushings as indicated.

10 In order to lock the ring 47 and with it the contact assembly in place, the springs 44 and 45 may be provided with grooves or kinks in which the ring 46 may rest in operating position, or the ring 47 may be carrying a projection or cam extending downwardly, 15 and the ring may be rotatable to lock the cam behind a projection in the shell member 27'. No details of this nature have been shown in order to keep the drawing as simple as possible. It will be understood that there are a 20 great number of possible ways for securing the contacts in place in the manner intimated.

Referring now to Figs. 12 to 17, inclusive, these figures illustrate a preferred form of carrying out the invention. The heater shown 25 therein is provided with four movable heating elements. Normally these elements are in a position to form a large oval tubular opening which may be used when it is desired to apply a Marcel wave to receive a 30 strand of hair wound on the prongs of a curler fork. Now, when it is desired to apply an ordinary round curl wave, the operator merely moves knobs on the outside of the heater, thereby displacing the heating elements in 35 such a manner that they form a small, round tubular opening suitable for receiving a strand of hair arranged on the usual curler rod. The figures will now be explained in detail.

40 Fig. 12 is a longitudinal cross section of the modified heater, and Fig. 13 is a transverse cross section. As seen more clearly from Fig. 13, there are four heating elements provided, designated with reference numerals 59 to 62, inclusive. These elements are mounted inside of the shell member 50 and are 45 slidable in grooves on guide members such as the one shown in Fig. 16. The elements 59 and 60 have normally a tendency to move 50 toward the center which is due to the action of spring 77 and 78 shown clearly in Figs. 13 and 14, while the elements 61 and 62 have normally a tendency to move away from the center, which tendency is due to the mounting 55 springs 86 to 89, best shown in Fig. 12.

Referring particularly to Fig. 13, it will be seen that the elements have freedom of movement within the limits provided by the projections 73 to 76, inclusive, of the guide member 50' shown separately in Fig. 16. The movement of the elements 61 and 62 away from the center is limited by levers 81 and 82 which are rotatably mounted on shafts 79 and 80 fastened in the shell member 50 as shown in Fig. 13. These levers have arms 79 and 80 which are adapted to slidably engage bearing-like projections of operating knob members 83 and 84. These knobs in turn are slidably mounted in openings 85 in shell 50. It will be clear from the above description with reference to the drawings, that the tendency of the elements 61 and 62 to pull away from the center will act on the lever arrangement, and the latter in turn will act on the slidable knobs pushing them upward in the openings 85 in shell 50, into a position shown in Fig. 12. Accordingly, the tendency of the other two elements to move toward the center, will be limited by the edges of the elements 61 and 62, and the entire arrangement will normally 60 assume a position as shown in Fig. 13, thereby producing an oval opening 59 large enough to receive the strand of hair on a curler fork for applying a Marcel wave. In case it should be desired, however, to use the heater for applying a round curl wave, all that is necessary is to operate the two knobs 83 and 84. The elements 61 and 62 will thereby be moved toward the center against the tension of springs 86 to 89, inclusive, and will displace 65 the elements 59 and 60 against the force of springs 77 and 78. The elements will position themselves as shown in Fig. 17, producing a small round tubular opening for receiving hair arranged on a curler rod.

When the elements are in the position to receive the curler fork, as shown in Fig. 13, they are connected to current as shown in the wiring diagram in Fig. 15. Each element is a unit in itself. It consists of a cover shell 100 which encloses an electrical heating member of suitable design, as for example the member 76 of element 61, which is insulated to the outside by the insulator 88. The structure of the other elements is similar as seen 105 from the drawing, Fig. 13. The heating members are connected in series, as for example the members 67 and 69 of the elements 61 and 62, and the two pairs of elements again are connected to current in parallel, as 110 shown in Fig. 15. Each element is provided with a cover plate of insulating material, such as indicated at 90, 91 and 92 which are the cover plates of elements 61, 59 and 62, respectively. These cover plates carry contact members such as indicated at 93, 94 and 95. In the upper part of the shell 50 is mounted an insulating plate 52 which carries the terminals 55 and 56 for the current supply conductors 53 and 54. side of the plate 52 are mounted two stationary contact members 57 and 58. Assuming that the elements are in the position shown in Fig. 13, and comparing this figure with the 5 wiring diagram shown in Fig. 15, it will be seen that the contacts 93 and 95, which are the contacts mounted on the elements 61 and 62 respectively, are in engagement with the contact members 57 and 58. The heating 10 members 67 and 69 of these elements are connected in series as shown. The element 59 has a contact 94 which is at this time in engagement with the contact member 57 on the insulating plate 52, and the element 60 is 15 provided with a corresponding contact 96 which is in engagement with the contact member 58. The heating members 63 and 65 which belong to the elements 59 and 60, respectively, are again connected in series. 20 Thus the four elements are connected in pairs in parallel to the current supply conductors as is illustrated in Fig. 15. When the knobs 83 and 85 are operated to position the elements as indicated in Fig. 17, the contacts 25 94 and 95 of elements 61 and 62 will slide toward the center along the contact members 57 and 58, while the contacts 94 and 93 of the elements 59 and 60 will slide off from the contact members 57 and 58 and will thus 30 connect these elements because in this position the elements 59 and 60 are not needed.

The above described form of carrying out the invention shows a structure in which the heater is closed at its upper end by a cap 35 member 51. This structure, it will be seen, corresponds to the structure of the heater shown in Fig. 1. In practice it is desirable to use a heater which has a tubular opening extending throughout its entire length, because of the steam and heat developed during 40 the process of baking a strand of hair in place. Therefore, the modifications in Figs. 10 and 11 have been shown in which the openings extend throughout the length of 45 the heaters. The structure illustrated in Figs. 12 to 17, inclusive, can of course be arranged in a manner similar to the one shown in Figs. 10 and 11. The heater has been shown closed at its upper end because of the 50 fact that the appliance is not limited to be used in connection with permanent waving machines, but may be used with advantage in a number of industrial processes. However, when used for the purpose described in 55 this specification, the device should be made according to the structure shown in Figs. 10 and 11, i. e., with the opening extending throughout its length. This can be easily done by substituting an insulating member 60 with an opening for the member 52 which is shown solid. The contacts may be arranged on this member in a simple manner, the details of which may be omitted in order to 65 avoid unnecessary encumbering of the specification. Instead of a cap-like cover 51 as

shown in Fig. 12, a ring may be used which carries the current supply conductors and embraces the upper end of the shell member 50. When carried out in accordance with the above, the opening is preserved in every 70 position of the heating elements, and steam or heat developed during hair treating can readily escape. However, when used for other industrial purposes, it may be desirable to adopt exactly the structure shown. 75

Concerning the heat insulating and heat concentrating qualities of the last described heater, it will be seen that each element is separately insulated to the outside, to prevent heat radiation away from the center which is the place of use. In addition to this insulation it will be observed that the movable elements are in any position separated from the shell member, which represents a very effective insulation against heat 80 radiation to the outside since air is the worst heat conductor. Therefore, the outer shell will always be cool during the entire process.

We have described and illustrated certain 85 embodiments of the invention, but it will be understood that we do not desire to be limited either in its application or in its structure beyond and above the limitations defined in the following claims.

What is claimed is:

1. A heat treating device comprising a plurality of heating elements forming a tubular opening of a certain size, means for altering the size of said opening, and means operated thereby for disconnecting certain of 100 said elements from common current supply terminals provided in said device.

2. A heating device having a tubular opening for receiving an article for heat treatment, current supply terminals in said device, heating elements connected thereto, means for altering the size and shape of said tubular opening, and means for thereby altering the connection between said terminals and said 105 elements.

3. A heating device comprising a plurality of heating elements and having a tubular opening for receiving an article for heat treatment, terminals for supplying current to said elements, means for altering said tubular opening to receive a different article for heat treatment, and means for changing thereby the connection between certain of said elements and said terminals.

4. A heating device having a tubular receptacle for embracing an article for heat treatment, heating elements, common current supply terminals therefor, means for moving said elements with respect to each other for changing said receptacle to embrace a different article for heat treatment, and contact means actuated thereby for altering the connection between said elements and said terminals.

5. A heat treating device of the class de- 130

- scribed, comprising a plurality of variably used heating elements, each of said elements having individual heat generating means and provisions to insulate the outside against heat generated thereby, common current supply means connected to one of said elements, and co-operating contact means in each of said elements for automatically connecting said supply means only to the element in use.
6. A heat treating device of the class described, comprising a primary element having a tubular heating member, heat generating means and insulating means for directing toward said member heat generated thereby, current supply means permanently connected to said primary element, a secondary element adapted to be attached to said primary element and having a heating member, heat generating and insulating means similar to said primary element, and co-operating contact means on said primary and said secondary elements for disconnecting said current supply means from said primary element and for connecting the same to said secondary element.
7. A heat treating device of the class described, comprising a primary heater having a tubular heating member, a heating element, insulating means in said heater for directing toward said member heat generated by said element, contact means connected to said element, current supply conductors terminating in said contact means, a secondary heater adapted to be attached to and removed from the heating member of said primary heater and having a heating member, a heating element and insulating means similar to said primary heater, and contact means on said secondary heater cooperating with the contact means of said primary heater when attached thereto, for disconnecting the heating element of said primary heater and for substituting the heating element of said secondary heater.
8. A heat treating device of the class described, comprising a primary heater having a tubular heating member, a heating element disposed around said member, insulating means covering said element, contact means connected to said element, current supply conductors terminating in said contact means, a secondary heater adapted to be inserted into the heating member of said secondary heater and having a heating member, a heating element and insulating means similar to said primary heater and similarly disposed, and contact means on said secondary heater cooperating with the contact means of said primary heater for disconnecting the heating element of said primary heater and for substituting the heating element of said secondary heater when the same is inserted into said primary heater.
9. A heat treating device comprising a first heater having a tubular heating mem-
- ber, a heating element disposed around said member, insulating means covering said element, stationary contacts connected to said element, movable contacts cooperating with said stationary contacts, current supply conductors terminating in said movable contacts, a second heater adapted to be inserted into the heating member of said first heater and having a heating member, a heating element and insulating means similar to said first heater and similarly disposed, and contact means on said second heater cooperating with the movable contacts on said first heater for disconnecting the heating element of the first heater and for substituting the heating element of the second heater when the same is inserted into said primary heater.
10. A heat treating device comprising a tubular member, a second tubular member insertible into the first tubular member, heating elements carried by the respective members, means for supplying electrical energy to said elements, and means controlled by the second tubular member for opening the circuit of the first member and closing the circuit of the second member when the latter is inserted into the former into operative relation thereto and for closing the circuit of the first tubular member and opening the circuit of the second tubular member when the latter is withdrawn from the former.
